Inventor

Alexis R. Pribil,

UNITED STATES PATENT OFFICE.

ALEXIS R. PRIBIL, OF CLEVELAND, OHIO.

DESIGN FOR A CONNECTING-ROD.

52,495.

Specification for Design. Patented Sept. 24, 1918.

Application filed December 6, 1917. Serial No. 205,900. Term of patent 14 years.

To all whom it may concern:

Be it known that I, ALEXIS R. PRIBIL, a citizen of the United States, residing at Cleveland, in the county of Cuyahoga and State of Ohio, have invented a new, original, and ornamental Design for a Connecting-Rod, of which the following is a specification, reference being had to the accompanying drawing, forming part thereof.

The figure is a perspective view of a connecting rod, showing my new design.

I claim:

The ornamental design for a connecting rod, as shown.

ALEXIS R. PRIBIL.

Witnesses:

ANNA M. DORR,

KARL H. BUTLER.
